(57) **CLAIM**

The ornamental design for a vehicle mirror, as shown and described.

DESCRIPTION

FIG. 1 is a top, front and left side perspective view of a vehicle mirror showing my new design, the right side being a mirror image of the left side shown;

FIG. 2 is a front elevation view of the embodiment of FIG. 1;

FIG. 3 is a rear elevation view of the embodiment of FIG. 1; and,

FIG. 4 is a cross sectional view thereof taken along line 4—4 of FIG. 3.

The bottom view of the design is plain and unornamented. The broken lines shown in FIGS. 3 and 4 are for illustrative purposes only and form no part of the claimed design.
